UNITED STATES PATENT OFFICE.

ERNEST J. KNABE, JR., AND HENRY MALLEBRE, OF BALTIMORE, MARYLAND, ASSIGNORS TO THE WM. KNABE & CO. MANUFACTURING COMPANY OF BALTIMORE CITY, OF BALTIMORE, MARYLAND; A CORPORATION OF MARYLAND.

COMBINED MANUALLY AND MECHANICALLY OPERATED PIANO.

No. 887,687.

Specification of Letters Patent.

Patented Dec. 4, 1906.

Application filed June 8, 1905. Serial No. 263,566.

To all whom it may concern:

Be it known that we, ERNEST J. KNABE, Jr., and HENRY MALLEBRE, citizens of the United States, residing at Baltimore city, in the State of Maryland, have invented certain new and useful Improvements in a Combined Manually and Mechanically Operated Piano; and we do hereby declare the following to be a full, clear, and exact description of the invention, such as will enable others skilled in the art to which it appertains to make and use the same.

This invention relates to combined pneumatic and manually-operated instruments in which the mechanical player is incorporated in the construction of the piano. These instruments may be played manually by fingering the keyboard or mechanically by operation of the pneumatics upon the piano-action.

The main objects of our invention are, first, to preserve the same quality of touch when the instrument is played manually as in standard manually-operated pianos and, second, to prevent the bobbing up and down of the keys while the instrument is being operated mechanically. These objects are attained by improved mechanism, substantially as illustrated in the accompanying drawings, which represent one preferred embodiment of our invention, and are to be taken as a part of this specification.

The invention will hereinafter be fully described with reference to said drawings and then particularly pointed out and defined in the appended claims.

In said drawings, Figure 1 is a cross-sectional view through the keyboard and action of a piano, showing the mechanism of the piano-action associated with one key and the corresponding hammer actuated thereby. This view illustrates the action of the instrument when played manually. The full lines show the position of the mechanism when the key is up and the dotted lines show the position of the mechanism when the key has been depressed. Fig. 2 is a view similar to Fig. 1, illustrating the action of the instrument when operated by the mechanical player. The full lines represent the normal position of the mechanism and the dotted lines indicate the movement of the mechanism by the pneumatic striker. Fig. 3 is a fragmentary

section taken transversely of the key behind the locking-rail and looking toward the piano-action. Fig. 4 is a detail perspective view showing the upper and lower front panels of the piano-case, a device for automatically opening the lower panel whenever the upper one is opened, and the locking-rail actuated by the same device for automatically locking the keys while the instrument is played mechanically.

The invention being applicable to any ordinary self-playing and manually-operated instrument, we have illustrated a piano-action of conventional type wherein the hammer is actuated in the usual way by its under lever or the rocker or wippen 2, pivoted to the under side of the action-bar 1.

The piano-keys 3 when fingered act upon the vertically-arranged rods 4, which actuate the rockers or wippens 2 to cause the hammers to strike upon the strings. The strikers of the pneumatics act upon the same rods 4 to actuate the piano-action when the instrument is operated mechanically. As will be seen, these two means for actuating the action are entirely independent.

Preferably the rod 4 is not positively connected with the wippen 2. Instead it is equipped at its head with a wedge-shaped piece 5, which engages in a curved or rounded notch in the under side of the wippen. The lower part 6 of the rod is thin and passes loosely through a slot in the rear end of the key or key-lever 3. Above the rear end of the key-lever at the point 7, where the rod is thicker and threaded, the capstan-screw 8 is screwed thereon, resting upon the rear end of the key, which thereby lifts the rod when the front end of the key is depressed by the performer's finger. This capstan-screw allows regulation of the length of the rod acting between the rear of the key-lever 3 and the wippen 2 of the piano-action. At its lowest point the rod is swelled into a head 9, which rests upon the upper end of a vertically-movable rod or striker 10, this being the striker of the pneumatic playing apparatus. Said rod 4 slides up and down in bearings 11, the upper one above the key and the lower one below the key. These bearings may be guide-bearings in rails arranged in the piano-case longitudinally of the keyboard. The upper bearing 11 prevents the rod from moving

laterally, but allows a slight forward and backward movement, so that the head of the wedge 5 can accommodate itself to the slight arc in which it is caused to travel by 5 reason of the member 2 being pivoted or hinged. The lower bearing allows only an up-and-down movement.

The number 12 denotes supporting-brackets for the upper bearing-rail.

10 It is observed that the rod is supported both by the rear end of the key or key-lever and the pneumatic striker; but there is no positive connection with either. Hence the piano-action through the medium of the rod 15 4 may be operated by the key without affecting the striker or by the striker without affecting the key, since the thin portion 6 of the rod passes loosely through the slotted rear end of the key. By reason of absence 20 of any positive connection between the pneumatic striking mechanism and the rod or between such mechanism and the key the manipulation of the keys operates the piano with the same ease and quality of touch attainable in standard manually-played instruments, since the keys are free to move as usual without lifting or otherwise exerting force in movement of the strikers or any part of the mechanically-operated mechanism, 25 and the weight of the rod 4 is no greater than that of the ordinary abstract or extension rod of such standard instruments. On the other hand, by reason of absence of positive connection between the key-lever and the 30 rod and between the key-lever and the striker the operation of the piano-action by the strikers of the pneumatic apparatus is effected without movement of the keys, which may be locked during automatic playing by means hereinafter to be described, thus preventing the bobbing up and down of the keys, which is so annoying to many performers. Furthermore, our construction is exceedingly simple and compact and avoids 35 complications or interference with either the piano-action or the strings.

To maintain the front ends of the keys in their normal elevated position during the operation of the piano by the pneumatic apparatus, we utilize a movable rail 13, which in one position allows free manipulation of the keys, while in another position it bears against or upon the rear portions of the key-levers and holds them down, thus preventing 50 the front ends of the keys from moving downward from their normal position. This locking-rail 13 is of course arranged behind the pivots of the keys and is shown hinged to brackets or standards 14, which are located 55 in the opposite sides of the piano-case or at opposite ends of the keyboard.

The rail is operated by a revoluble actuating-rod 15, having a crank 16 slidably connected with the rail, as by passing said crank 60 through a loop 17 at the front side of the rail.

In one position of the actuating-rod 15 the rail is held out of contact with the rear portions of the keys, thus allowing free movement thereof when the keyboard is fingered, while in another position the crank 16 forces 70 the rail into contact with the key-levers. As shown, the lower edge of the rail engages, upon the hump 18 on the upper side of the key-lever, when the rail is forced to locking position by the actuating-rod. Said actuating-rod 15 is a member of an automatic pedal-exposing device, such as shown and described in the pending application of Ernest J. Knabe, Jr., filed April 1, 1905, Serial No. 253,226, the function of said device being to 80 automatically open the lower front door or panel which covers the pedal movement in the lower part of the case whenever the performer opens the upper front panel in the upper part of the case. 85

19 denotes the sliding front panel in the upper part of the case, behind which is contained the usual mechanism (not shown) for controlling the pneumatics, (tracker-bar traversed by a perforated web or note-sheet.) 90 At the rear side of the said panel is a wedge or trippet 20. When the panel is slid open for the purpose of placing the music-roll in position when the instrument is to be mechanically operated, the wedge or trippet 95 20 engages an arm 21 on the actuating-rod 15, and thereby turns said arm, causing its crank 16 to force the locking-rail 13 into engagement with the rear ends of the key-levers. 100

At the lower end of the actuating-rod 15 is an arm 22, which engages the upper end of an intermediately-fulcrumed lever 23, the lower end of which lever serves as a latch and engages in a notch or socket in the upper 105 edge of the hinged lower trap-door 24, being held therein by the spring 25. When the upper panel 19 is slid open, the same turn of the actuating-rod 15 which forces the locking-rail 13 upon the key-levers also 110 rocks the lever 23 against the resistance of the spring 25, thus unlatching the lower trap-door and allowing it to fall outward and expose the pedals of the automatic player. The locking-rail 13 may also be operated by 115 a link or wedge connection with a vertically movable actuating-rod in the event of employing such a vertically-movable rod for operating the lower trap-door, as illustrated in two alternative forms in the aforesaid application of Ernest J. Knabe, Jr. 120

Having thus fully described our invention, what we claim as new, and desire to secure by Letters Patent of the United States, is—

1. In a combined manually and mechanically operated instrument, the combination of a key-lever, a wippen-actuating rod 125 supportable and operable thereby, said rod passing loosely through the key-lever and liftable independently thereof, and a mechanically- 130

- operated striker operating on the rod below the key-lever.
2. In a combined manually and mechanically operated instrument, the combination of a key-lever, a mechanically-operated striker or lifter arranged and operating under the rear end of the key-lever, and a wippen-actuating rod vertically disposed above the rear end of the key-lever and extending through the same, said rod being directly supportable and operable both by the key-lever and subjacent striker, there being no positive connection between the rod and key-lever or striker, nor between the key-lever and striker.
3. In a combined manually and mechanically operated instrument, the combination of the rocker or wippen of a piano-action, a key-lever, a rod for actuating the wippen passing through a slot in the rear end of the key-lever and having a shoulder resting on said key-lever, and a mechanically-operated striker operating on the lower end of said rod.
4. In a combined manually and mechanically operated instrument, the combination of the rocker or wippen of a piano-action, a key-lever, a vertically-movable rod for actuating the wippen having a thin portion entered loosely through a slot in the rear end of the key-lever, a capstan-screw screwed upon said rod above the key-lever and resting thereon, and a mechanically-operated striker operating on the lower end of said rod.
5. In a combined mechanically and manually operated instrument, the combination of the rocker or wippen of a piano-action, a key-lever, a vertically-movable rod for actuating the wippen having a wedge-shaped head engaging in a notch in the under side of said wippen, said rod having a thin portion passing loosely through a slot in the rear end of the key-lever and having a swell or enlargement at its lower end, a capstan-screw screwed on said rod above the key-lever and resting thereon, and a mechanically-operated striker operating on the lower end of said rod.
6. In a combined manually and mechanically operated instrument, the combination of a key-lever, a wippen-actuating rod passing loosely through the key-lever, an adjustable capstan-screw supported by the key-lever and supporting said rod, whereby the rod is operated by the key-lever, and a mechanically-operated striker operating on the rod below the key-lever.
7. The combination of a key-lever, a mechanically-operated striker below the rear end thereof, a wippen-actuating rod vertically disposed at and extending through the rear end of the key-lever above the subjacent striker and directly liftable thereby, and means whereby said rod is directly supportable and liftable by the key-lever, said means being adjustable to regulate the operative length of said rod above the key-lever.
8. The combination of a key-lever, a mechanically-operated striker disposed below the key-lever, a wippen-actuating rod extending through at the rear end of the key-lever, and means for lifting said rod either from the key-lever or striker.
9. The combination of a key-lever, a wippen-actuating rod extending through at the rear end of said key-lever and supported thereby, said rod being operable by said key-lever, and a mechanically-operated striker or lifter operating on the lower end of the rod below the key-lever.
10. In a combined manually and mechanically operated instrument, the combination of the manual-keys, a movable element, a movable pedal-cover, mechanism for locking and unlocking said pedal-cover, the unlocking of said cover being accomplished automatically by the movement of said element, and a key-locking device operated by said mechanism.
11. The combination of the manual-keys, a pedal-exposing mechanism, and means operated thereby for locking the keys.
12. The combination of the key-levers having shoulders thereon, a hinged locking-rail arranged transversely of the key-levers and normally out of contact therewith, allowing free movement of the keys, and means for moving the rail into contact with said shoulders to lock the keys.
13. The combination of the key-levers, a sliding tracker-bar cover, a hinged locking-rail arranged transversely of the keys, and a vertically-disposed revoluble rod actuated by the opening movement of the tracker-bar cover and operating on said locking-rail to move the same into contact with the key-lever.
14. A combined manually and mechanically operated instrument having, in combination, upper and lower front doors or movable panels in the case for covering respectively the pneumatic operating or controlling devices and the pedal movement, and a connecting mechanism between said panels for automatically effecting the opening of the lower one by the opening of the upper one, a piano-action, key-levers for actuating the instrument manually, strikers for operating the same mechanically, there being no connection between the key-levers and the strikers, and a locking device for the key-levers actuated by the said connecting mechanism.
15. In a self-playing piano, the combination of keys, a device for playing the piano without the use of said keys, said device being provided with pedals, said keys being normally free to operate, locking means for the pedals and means for simultaneously locking

said keys against action and unlocking the pedals for action.

16. In a self-playing piano, the combination of the keys, a device for operating the piano without the use of said keys, said device including pedals and interlocking devices between said keys and said device whereby the keys are locked when the pedals are unlocked, and vice versa.

17. In a self-playing piano, the combination of a device for playing the piano without the use of keys, said device including pedals,

keys normally free to be operated by a player, a lock for the keys and means for locking said pedals out of action as long as the keys are free to be operated.

In testimony whereof we affix our signatures in presence of two witnesses.
